United States Patent

Des. 240,325
Patented June 22, 1976

240,325

RIBBED METAL PANEL

Donald H. Landis, Pittsburgh, and Richard C. Pfaff, Murrysville, Pa., assignors to Epic Metals Corporation, Braddock, Pa.

Original design application Jan. 15, 1973, Ser. No. 323,912. Divided and this application Feb. 10, 1975, Ser. No. 548,499

Term of patent 14 years

Int. Cl. D25—01

U.S. Cl. D25—75

FIG. 1 is a perspective view of a ribbed metal panel showing our new design.

FIG. 2 is an end view of the panel of FIG. 1 showing the rib profiles and connecting panel portions.

This application is a division of application Ser. No. 323,912, filed Jan. 15, 1973.

We claim:

The ornamental design for a ribbed metal panel, substantially as shown.
